UNITED STATES PATENT OFFICE.

CLEMENT P. GRIFFITH, OF FORT WAYNE, INDIANA, ASSIGNOR TO S. F. BOWSER & CO., INC., A CORPORATION OF INDIANA.

APPARATUS FOR RECLAIMING USED LUBRICATING OIL AND FUEL SUBSTANCES.

Application filed August 1, 1921. Serial No. 489,143.

To all whom it may concern:

Be it known that I, CLEMENT P. GRIFFITH, a citizen of the United States, residing at Fort Wayne, in the county of Allen and 5 State of Indiana, have invented certain new and useful Improvements in an Apparatus for Reclaiming Used Lubricating Oil and Fuel Substances.

The invention relates to an apparatus 10 adapted to be used in practicing the invention, and it is the primary object of the invention to provide an apparatus to be used in purifying used lubricating oils whereby valuable parts of the lubricant may be rendered fit for subsequent use and all wasted 15 and condensed fuel substances may be recovered for use as a by-product.

It is a further object of the invention to provide an improved apparatus in which 20 gasoline and other volatile fuel oils which become mixed with lubricant in the crank cases of gas engines may be recovered and not be permitted to pass off in the reclaiming process as a waste vapor or gas as hereinbefore practiced in reclaiming used motor 25 lubricating oils.

It is a further object of the invention to provide improved apparatus for drawing off from a treating tank a stratum of 30 reclaimed lubricating oil and at the same time allowing the non-usable stratum or part of the oil being treated to remain in the treating tank or chamber.

Other objects of the invention will appear 35 from the following description, which is directed to my improved apparatus which is shown in detail in the drawings, in which Fig. 1 is a side elevation of my complete apparatus with portions only of the piping 40 systems leading therefrom being broken away.

Fig. 2 is a detail of the draw-off apparatus in the treating tank, a portion of the tank adjacent to said apparatus being shown in 45 broken section.

Fig. 3 is a horizontal section through the 50 treating tank being taken on line 3-3 of Fig. 1 looking downwardly, as indicated by the arrows.

Fig. 4 is a horizontal section taken 55 through the top of the separator unit on line 4-4 looking downwardly, as indicated by the arrows in Fig. 1.

Fig. 5 is a section through one of the 55 water and steam coils in the bottom of the

treating tank of Fig. 1, illustrating the manner in which the water and steam vents are formed to effectively direct the fluid under pressure against the tank bottom.

The reference character 10 designates generally the walls of a treating tank which may be supported in any desired manner upon a floor, stand or other suitable support, as the legs indicated by reference characters 11 and 12. It is preferable, although not necessary, to construct the bottom of the tank in the form of an inverted cone providing the draw-off pipe 13 controlled by valve 14 at the lower-most portion of the bottom, which latter is indicated by reference character 10^a. Likewise it is preferred by me to construct the top closure member for the cylindrical tank 10 in the form of a cone, which is indicated by reference character 10^b. For the purpose of introducing oil into the tank to be treated I provide the inlet pipe 15 through which dirty oil to be treated may be pumped. Near the bottom of the cylindrical portion of the treating tank 10 there is a coil or pipe 16 which may extend peripherally around the interior of the tank bottom. This coil 16 will preferably serve as the terminal for an inlet pipe 17 which passes outwardly through the wall of the tank as at 18. Just on the outside of the tank this pipe 17 is connected with a branch fitting 19 which takes the pipes 20 and 21, one of which may communicate with a suitable source of water supply, and the other of which may communicate with a source of steam supply, whereby either water or steam under the control of the valves indicated in the said pipes may be admitted into the coil 16 on the interior of the treating chamber accordingly, as may be desired in carrying out the steps of my process. The coil 16, a portion of which is shown in section in Fig. 5, will preferably be provided with a number of openings on the bottom side thereof somewhat staggered as indicated by reference characters 22, 23 from which it will be seen that jets of water or steam, accordingly as water or steam is admitted into the coil, may be projected in angular relation to the bottom 10^a of the treating tank 10.

In carrying out the principles of my invention I first admit a quantity of dirty motor oil or other material to be treated into the tank 10 through the pipe 15 with all

- gravity outlets of course to the tank closed. When a suitable quantity of dirty oil is within the tank, say anywhere below the opening which is controlled by the relatively 5 large screw threaded closure member 24, I remove the member 24 and place on the interior of the tank a quantity of suitable alkaline substance, preferably such as soda ash or a common commercial alkaline wash- 10 ing powder. The soda ash, or other similar alkaline substance will thus serve in the dirty oil as a coagulant for the purpose of inducing saponification and after the soda ash or its equivalent is introduced the hand 15 valve 30, in the steam pipe 20 will be opened and live steam introduced into the coil 16, which will be discharged through the vents 22, 23 and cause a violent agitation of the dirty oil on the interior of the treating tank. 20 The reclaimer tank 10 is preferably of consider- able size although its size may be varied according to the amount of oil treated. In the use of my improved apparatus I prefer to pump into the tank 10 any desired quantity, 25 as for example, five hundred gallons of dirty oil and add thereto before steaming, through the opening closed by the plate 24, approximately seventy-five pounds of soda ash or equivalent material, and if smaller or greater 30 quantities of oil are treated, obviously, the same conditions will govern as to the proportions to be used of the coagulant.
- After the oil and soda ash are in the tank the steam valve 30 may be opened wide 35 until the contents of the reclaimer are raised to approximately 210 to 212 degrees Fahrenheit, after which the steam will pass through the oil without condensing. After the material being treated reaches the ap- 40 proximate temperature of the steam the amount of steam introduced may be considerably diminished. The action of the steam will immediately drive from the dirty oil being treated in the tank all the light 45 volatile substances. It should be noted in this connection that in the case of lubricating oil taken from the crank cases of gas and gasoline engines the oil if used over an extended period will be found charged 50 with unburned fuel such as gasoline, and it has been found that used lubricating oil from gasoline engines frequently contains anywhere from 10 to 15% or more of unignited gasoline or other light oil. Dur- 55 ing the steaming process therefore all the gasoline, naphtha and other light substances will vaporize and will pass off from the liquid being treated in the tank and out through the conical top 10^b and the perfora- 60 tion at the extreme top thereof into the pipe 31 leading to the condensing coil 32, which is contained within a water jacket or tank 33 having an inlet pipe 35 and a discharge pipe 34 whereby a suitable cooling element 65 as water may be caused to surround the con-

densing coil 32. As the lighter oils coming through the discharge pipe 31 from the treating tank reach the coil 32 in the condenser the temperature of the same will be reduced so that condensation will take 70 place and such oils will in the form of liquid mixed with water be discharged through the connection 36 into the separating de- 75 vice consisting of the compartment 37. The water jacket or tank 33 supplying the cool- ing medium to the condensing coil 32 may be supported in any desired manner as by a base consisting of legs, as indicated by reference characters 38, 39 and 40 with suitable connecting or bracing means, as in- 80 dicated by reference character 41. The con- densing compartment 37 may be supported in any suitable manner as on a base con- 85 sisting of legs 42, 43 and 44 and connecting and strengthening pieces as indicated at 45. The compartment 37 is provided with spe- 90 cial separating devices whereby condensed water and the light oils as gasoline, which will accumulate therein, may be separated by gravity, due to the different specific 95 gravities of the fluids in the mixture coming from the condensing coil 32. In order to secure the desired degree of separation I provide an oil draw-off receiving device or funnel 49 and pipe 46 which is supported by and passes through the wall of com- 100 partment 37 with a discharge nozzle or spout 47 positioned on the outside of the com- 105 partment to discharge into a receptacle 48 intended to receive the gasoline or fluids of similar specific gravity in the nature of fuel oils to be extracted from the dirty lub- 110 ricing oil in the process of reclaiming. The water draw-off pipe 51 after passing inwardly through the wall of the com- 115 partment 37 is also deflected upwardly to near the upper end of the compartment 37 and some distance above the inlet port for the products of condensation coming from the coil 32, and is preferably provided at its upper extremity with a receiving device or funnel 52 of a construction similar to the funnel 49. The upper receiving edges of the funnel members 49 and 52 are both arranged a short distance above the inlet opening of the connection 36 and the oil re- 120 ceiving funnel 49 is located in a plane slight- 125 ly above the plane of the upper end of the funnel 52, which is intended to receive the water overflow. The compartment 37 is divided by a vertical partition 53, which is attached to the side walls of the compart- 130 ment at diametrically opposite portions of the walls dividing this compartment into two separate compartments that are closed from each other except at the bottom of plate 53, where there is an opening design- 135 ated by reference character 54 affording communication between the two divisions of the compartment on one side of which the

products of condensation are received and which contains the oil draw-off or discharge device, while the compartment on the other side of the partition contains the water draw-off or discharge funnel 52.

Another important feature of my improved apparatus is that when the treatment tank for reclaiming the dirty lubricating oils is equipped in the manner herein described there are no gases allowed to escape to atmosphere as practically everything including steam and vaporized oil is condensed and collected and separated in the apparatus in the manner described. Heretofore one of the objections to oil reclaiming apparatus especially when used in densely populated communities has been the escape of obnoxious gases during the reclaiming operation.

The draw-off apparatus preferably consists of a pipe 60 which extends through the wall of compartment 10, as illustrated in the drawings, somewhat below the middle portion thereof and is swivelly mounted to have rotation in a supporting plate 61. The plate 61 has a hub portion at 62 adapted to extend through an opening in the wall 10 of the treating tank and in order to furnish a liquid tight connection with the discharge tube or pipe 60 journalled therein will preferably be screw threaded at its inner extremity and provided with a co-operating gland nut 63 between which and the hub portion 62 suitable packing material, not shown, may be inserted. The plate 61 will also be provided with a threaded hub portion on the exterior, as indicated by reference character 64, and adapted to take a co-operating screw threaded gland nut 65 beneath which in a like manner may be placed packing material to secure a liquid tight connection with the pipe 60, and at the same time allow the pipe 60 to rotate freely within the plate 61 and the hub portions formed integrally therewith. It will be seen that the purpose of thus mounting the oil discharge pipe 60 in this connection with the wall of the treating tank 10 will be to enable it to have a rotatable movement on its longitudinal axis and to this end on the exterior of the gland nut 65 I clamp an operating handle 66 having a suitable hand receiving portion as illustrated in Figs. 1 and 2 with the two-part clamp at one end adapted to encircle the pipe or tube 60 and be clamped thereto by suitable retaining bolts or screws, as illustrated by reference character 67, Fig. 2. The pipe 60 on the exterior of the operating handle or lever 66 may then be screw threaded and provided with a suitable valve controlled faucet 68 having a downwardly discharging nozzle 69, the valve portion therein being under the control of an operating handle 70. The nozzle portion 69 will be directed over the

top of a suitable funnel 71, the discharge portion of which will be connected with a pipe 72 terminating in a three-way valve 73 having two discharge pipes 74 and 75 respectively. The pipe 74 may lead to a suitable container for reclaimed oil and when the valve 76 is adjusted oil may flow through the funnel 71 out through a connection with pipe 75 into a tank for the reception of oil that is not suitable for lubricating purposes but yet too valuable to be discarded and hence, it will be collected and retreated at a subsequent reclaiming operation. In order that the operator may be enabled to see the character of the oil discharged from the reclainer through the discharge nozzle 69 into the funnel 71 I preferably coat the interior of the funnel 71 with some suitable material as nickel, which will enable the operator to see the degree of clearness of the oil being discharged into the funnel. Whenever during the discharge of the lubricant into the funnel the operator detects the presence of dirty oil he will adjust the three-way valve 76 so as to discharge from the clear oil tank to the dirty oil tank for further treatment.

At the inner end of the discharge pipe 60 on the interior of the treating tank 10 there is a three-way fitting 80 which has communicating therewith an upwardly extending pipe 81 and a shorter downwardly counterweight part 82. The pipe 81 at its upper extremity is open and is screw threaded and provided with a co-operating screw threaded closure cap 83 attached to a convenient hand operating member or lever 84, whereby the cap 83 will be accessible to the operator by removing the screw threaded covering 24 of the compartment and inserting his hand well into the tank. As soon as the cap 83 is removed from the upper extremity of pipe 81 the operator may then by grasping the hand lever 66 rotate the pipe 60 in the bearing aforesaid described, and incline the discharge pipe 81, 82 to whatever angle may be desirable to bring the upper end thereof into the zone of the reclaimed and purified oil. In the operation of the device the operator may operate the hand lever 66 after the cap 83 is removed until the reclaimed oil starts to run through the discharge faucet 69 into the funnel 71 and he may continue the inclination by successive stages as long as he continues to get a discharge of reclaimed oil of the desired degree of clearness from the apparatus, or to avoid continuous attention he may lower the open end of the pipe 81 to the bottom of the clear oil zone and allow the clear oil to discharge. After drawing off the reclaimed oil he may adjust valve 76 to discharge into the pipe 75 and continue the operation of the discharge lever 66 inclining the pipe 81 still further and draw off the

dirty oil for further refining as long as desired or until the pipe 81, 82 is inclined to the horizontal position, after which obviously, no further discharge may be had 5 through the faucet 68. If however, before the maximum discharge through the faucet 68 is obtained the oil shows qualities that would preclude a further reclaiming operation on it, then the faucet 79 may be closed 10 and what remains of sludge, water and other impurities in the tank will be in condition for discharge to the sewer or other waste receiving means through the discharge pipe 13 controlled by valve 14 in the bottom of 15 the tank. The remaining waste contents of the tank may generally be drawn off through the discharge pipe 13 at the bottom and the discharge of heavy sludge expedited obviously by the introduction of water or 20 steam through the coil 16, which will result in a thorough cleansing of the interior of the tank, when the reclaimer apparatus will be ready for the treatment of another batch of oil.

25 In order that the invention might be fully understood I have described the method in connection with the preferred embodiment of apparatus for use in carrying it out, but it is not desired to be limited to the details 30 shown, for it will be apparent that persons skilled in the art may resort to various modifications especially of the apparatus without departing from the purpose and spirit of my invention.

35 I claim:

1. A tank for reclaiming and separating mixed oils having a substantially L-shaped take-off pipe journaled in the side thereof, one angle of said pipe being normally vertically disposed within said tank and the other end of said pipe extending through and beyond the outer wall of said tank, the inner end of said pipe being screw threaded for the reception therein of a screw threaded 40 closure cap, a hand grip carried by said cap, a hand hole in the side of said tank adjacent the upper end of said pipe when in

normal position, and a closure cap for said hole.

2. In a device of the described character, 50 the combination with a closed treating tank having approximately vertical side walls with an opening therein, a bearing member secured in said opening of the tank wall and being provided with packing glands 55 whereby to form a fluid tight connection with a discharge pipe and at the same time to permit said pipe to rotate freely in said bearing member, a pipe in said bearing member having connected to the inner end thereof on the interior of the tank an angularly, normally upstanding pipe section, and being provided with a movable closure at the upper intake end thereof, a hand lever for rotating the pipe secured thereto on the exterior of the bearing member and on the exterior of the tank, and a valve controlled discharge faucet secured to the outer extremity of the pipe on the exterior of the tank. 70

3. In a device of the described character, the combination with a metallic receptacle having a vertical wall, there being an opening in said vertical wall, a pipe bearing secured to the said opening, a horizontal 75 pipe in said pipe bearing, means for rotating said pipe in said bearing secured thereto on the exterior of the tank, a valve controlled discharge faucet secured to the pipe on the exterior of the metallic receptacle, 80 a pipe fitting secured to the pipe on the interior of the metallic receptacle, a normally upstanding pipe section secured to the fitting and being screw threaded at its upper extremity, a detachable cap for closing 85 the threaded extremity of the pipe, and a counterbalance weight also secured to the pipe fitting on the interior of the metallic receptacle.

In testimony whereof I have signed my name to this specification on this 29th day 90 of July, A. D. 1921.

CLEMENT P. GRIFFITH.
